FLEXIBLE REFRIGERATING PACKAGE
PRODUCTION

Claude F. Brown, Chicago, Ill.

Application April 25, 1938, Serial No. 204,145

8 Claims. (Cl. 62—1)

This invention relates to a process of forming a flexible refrigerating package capable for use for maintaining articles in a refrigerated condition in much the same manner that solid carbon dioxide—so-called Dry Ice—maintains such perishable and/or melttable products in non-perishable and/or non-melttable condition, respectively, for portable delivery over reasonable periods of time.

10 The chief object of this invention is to produce a Dry Ice substitute, as it were, which will be less expensive and which will be devoid of certain well known objections inherent to the use of Dry Ice for the aforesaid purposes.

15 The chief feature of the invention consists in enclosing within a waterproof, flexible container, such as a sack of "bean bag" character, as it were, a brine solution, sealing the container and freezing the brine to solid form in said container.

20 It has been experimentally determined that substantially double the weight of solid brine has a low temperature maintaining capacity substantially equivalent to that of a single weight of solid carbon dioxide within its temperature limits; 25 or in other words, its refrigeration value or capacity is but half that of Dry Ice within said limits for substantially equal weights.

The portable Dry Ice delivery service has demonstrated that for retail delivery from small 30 stores to the consumer, the ratio of effectiveness is approximately one to five, due to the sublimation loss factor and is dependent upon dependable delivery of the Dry Ice to the retailer. This dependable delivery means in other words, the 35 retailer daily must anticipate his potential requirements in order to minimize his sublimation losses, otherwise, Dry Ice refrigeration for portable delivery is prohibitive at the present price for said refrigerant.

40 The present invention, therefore, has the peculiar advantage that there is substantially no loss in material and that the material may be rapidly and economically brought to a refrigerating condition for use as a refrigerant equivalent 45 to Dry Ice at a relatively low cost and thus the demand for the same can be provided for as the demand increases and by relatively economical means, as will hereinafter be pointed out.

To illustrate the economy of the invention, the 50 following are representative figures given by way of example only. If it is assumed there is available in a pound of Dry Ice 250 B. t. u. absorption capacity, and it is assumed the average cost of such Dry Ice is 3 cents per pound, irrespective of 55 sublimation losses, et cetera, before mentioned,

there is a 3-cent cost for refrigeration requiring 250 B. t. u. using Dry Ice. Two pounds of brine ice at approximately 0° Fahrenheit also has available for refrigeration, an absorption capacity of approximately 250 B. t. u. For refrigeration purposes, if the standard value per k. w. h. is utilized, this value being approximately 10,000 B. t. u.—but which actually is greater except under extreme low pressures, wherefore the 10,000 B. t. u. figure is here given—the ratio that two 10 pounds of brine ice bears to 1 k. w. h. of energy is that the equivalent two pounds of brine ice costs, exclusive of the water and salt cost which is practically negligible, $\frac{1}{40}$ of the cost of a k. w. h. of energy, which in many instances is 1½ cents 15 and throughout the country averages about 2 cents for power purposes in industrial establishments, such as ice cream plants. In other words, assuming a cost of 2 cents per k. w. h. of energy, which is above the average minimum rate charged 20 household consumers of energy for mechanical refrigeration in many localities, the cost of obtaining the refrigerating capacity in two pounds of brine ice is approximately .05 of 1 cent as compared with the 3 cents for Dry Ice before mentioned, except there must be added to this .05 25 of a cent the cost of the container and the cost of the brine.

The container, it is estimated, costs approximately $\frac{1}{4}$ cent so that the total cost of the equivalent brine ice refrigerant capacity as compared to Dry Ice, if the latter is applied bare to a product for refrigerating the same, is approximately 30 1¼ cents as to 3 cents.

These approximate figures, as stated, are given 35 by way of example only to illustrate the economy of the refrigerant of the present invention as compared with Dry Ice as a refrigerant, assuming no loss in storage or handling of either material.

If it is assumed that one quart of ice cream is to be held in a frozen condition for four to six hours, the same will require $\frac{1}{2}$ pound Dry Ice and similarly there will be required approximately 1 pound of brine ice to effect the same refrigeration under the same conditions, which is required for 40 use with the usual insulated package conditions 45 today applying to portable delivery service.

Merely by way of illustration, certain specific materials are hereinafter mentioned, although it is to be understood that other materials are 50 equally available, and the invention consequently is not to be limited by the recitation of such specific materials.

In the drawing, Fig. 1 is a perspective view of 55 one example of the refrigerating unit embodying

the invention and Fig. 2 is a sectional view taken on line 2—2 of Fig. 1 and in the direction of the arrows.

The example illustrated in the drawing includes a layer of kraft paper 10 having an interior leak-proof coating 11. The fold is indicated at 12, the side seam at 13, the bottom seal at 14 and the top seam at 15. The eutectic material, such as of brine character, is shown as ice 16 in Fig. 2 and 10 substantially fills the container.

One type of package, as previously suggested, is of "bean bag" character so far as the form is concerned. It may, however, be of any desired bag character. It must, however, be of water-proof character and must be flexible, within those degrees of waterproofing and flexibility necessary to successfully effect the invention.

The brine may be of any suitable concentration. One example is herein set forth. A 20% 20 brine freezes to solid brine ice and has a eutectic point of zero degrees F. 20% brine includes one gallon water, which is approximately 8.3 pounds water and approximately 2 pounds sodium chloride. Whenever lesser bulk is desired or calcium 25 chloride is available as a cheaper source of material, such as is incident to the production thereof of as a waste product from other industries, a lesser amount of calcium chloride may be utilized instead of sodium chloride.

30 A relatively cheap container which may be discarded by the ultimate consumer of the perishable or meltable merchandise, is a waterproof flexible paper bag, as stated. An example of such a bag, for instance, is one made of 50 lb. kraft paper 35 having a small percentage by weight of glycerine incorporated in the paper stock because it is advantageous to utilize such a type of paper, although it is not absolutely essential to the practicing of the invention since any paper stock having flexibility at low temperatures will be satisfactory.

40 This kraft paper is suitably waterproofed and in the present example, the inside surface of the bag is waterproofed by one face of the paper carrying a coating. One satisfactory coating is that 45 which includes 20 lbs. of chlorinated rubber per ream. This again, as stated, is only given by way of example. Such a material readily lends itself to sealing by heat, although sealing by heat 50 is not essential to the practicing of the process. There are other waterproofing materials of resinous, cellulosic and rubber or rubber like character that are also satisfactory for use. Merely by way of example as to the equivalent containers 55 available, a flexible relatively thin rubber like sack or bag that will properly function under low temperature conditions would serve equally as well, although as stated, the container following use of the product is intended to be discarded 60 and the cost of such a properly compounded rubber container exceeds that cost of a paper contained as previously described specifically hereinbefore.

65 One relatively simple form of bag, as stated, is of "bean bag" character. A sheet of the proper size of the glycerine impregnated paper having the waterproof coating thereon, is folded so as to form a tube. The seam is sealed by heat and pressure. This is because the material mentioned is of thermoplastic character. If the waterproof coating is of other character, either suitable sealing mediums or treatments may be employed to effect the seal.

70 Following formation into tubular form, one end of the tube is similarly sealed, then the tube 75

is filled approximately half full with liquid brine of the character described. The opposite end of the tube is then sealed. The resulting partially filled sack is laid on its side and subjected to low temperature, which forms in the sack the 5 solid brine or brine ice.

The choice of bag forming material is dictated not only by the item of cost and availability of materials but is also controlled by the fact that in the formation of brine ice, crystals are formed 10 and the container must be puncture proof so far as said crystals are concerned. This packaged brine ice at or below the eutectic point is then available for use to prevent melting of ice cream, sherbets and the like and other articles whose 15 eutectic point is higher and for the preservation of perishable articles.

It will be obvious from the foregoing that the only loss sustained in storage of this type of refrigerant is its loss of heat capacity by absorption of heat and this can readily be renewed by refreezing. In the manufacture of ice cream there is usually available a hardening room at a temperature of zero to 20° below F. and when once the brine ice is formed and the packaged 20 brine ice is stored in the hardening room or in a room at an equal temperature, the loss of refrigerating capacity is prevented. With the case of Dry Ice, however, there is a loss due to sublimation and any recovery thereof is more expensive 25 than initial production, and is beyond the facilities of the average ice cream manufacturer. The reason for this loss is that Dry Ice sublimates at approximately 110° below zero F., and the range of present day mechanical equipment is 30 such that such temperatures cannot economically be maintained for storage purposes; whereas, the holding temperature for solid brine ice can be maintained very economically.

35 It will be readily apparent that the retailers 40 can be supplied with partially filled packages of liquid brine and the same conditioned by the retailer to a package of solid brine ice. The equipment necessary for such processing is relatively inexpensive and is of the general character of the present household mechanical refrigerator. In larger communities it is more economical to fabricate the refrigerant ready for use in the ice cream manufacturing establishments or 45 the ice manufacturing establishment, and without 50 any special additional equipment.

55 While the invention herein has been described as utilizing a brine material, it is to be understood any other suitable material may be employed. Such material, however, must have a low temperature eutectic point. Other materials 60 are alcohol, glycerin, ethyl glycol and the like.

65 The container correspondingly must not only be waterproof but resistant to the passage of the ice forming material employed. In other words, 70 the coating is resistant to ice forming material employed, if the container is of paper or other equivalent stock not normally resistant to the passage of such ice forming material therethrough.

75 The term "flexible" as used herein and in the claims is intended primarily to designate a container for a freezable solution which container during the freezing operation will automatically change shape as required or necessary, so that rupture, leaking or permanent distortion of the container does not result in such freezing action incident to the volumetric increase in the formation of ice.

The term "flexible" as thus defined may or 75

may not include materials which are inherently elastic but said term expressly excludes sheet metal containers having a relatively permanent initial form which form if distorted in the solution freezing operation is not automatically resumed upon the melting of the included frozen medium.

The term "refrigerated" as used herein and in the claims, is intended to include the conditioning or maintenance of an object so that a predetermined temperature, and/or corresponding physical condition of the object can be obtained and/or maintained.

The full nature of the invention has been described in great detail in the foregoing description. The same, however, is to be considered as illustrative only and not restrictive in character.

The several modifications described herein as well as others which will readily suggest themselves to persons skilled in this art, all are considered to be within the broad scope of the invention, reference being had to the appended claims.

The invention claimed is:

- 25 1. The process of forming a refrigerating bag structure including forming a flexible, rupture- and leak-proof bag of relatively light material and with an open mouth, partially filling the same through the mouth with low temperature 30 point eutectic liquid, the bag material being proof against liquid passage therethrough, sealing the liquid in the bag, and then freezing to form cryo- hydrate ice, the bag structure merely flexing without rupture during the freezing step.
- 35 2. A refrigerating bag structure including a flexible, relatively rupture and leak-proof material arranged in bag formation and a low temperature point eutectic material permanently sealed therein, the bag formation permitting eutectic material expansion without rupture when refrigerated to ice, and preventing leakage therefrom when reduced to liquid form.
- 40 3. A structure as defined by claim 2, characterized by the bag being formed of a flexible paper layer with an inner rubber-like material layer co-extensive therewith and united thereto substantially throughout the contacting surface areas thereof.

4. A structure as defined by claim 2, characterized by the bag formation being of "bean bag" form.

5. A structure as defined by claim 2, characterized by the water volume being less than that of the sealed bag volume and in an amount such that the resulting ice volume therefrom is substantially the same as the volume of the sealed bag.

6. The process of forming a refrigerating unit 10 which includes the steps of partially filling a bag with a liquid capable of being formed into ice, the bag being characterized by its construction of material including relatively light paper stock and a layer of material thereon rendering said stock proof against the action of such liquid, said bag being flexible, and proof against rupture as a result of repeated handling or flexing during freezing and thawing, sealing the liquid in the bag to form a leak-proof unit, and freezing the liquid in the bag to a substantially solid ice 20 condition.

7. A refrigerating unit comprising a bag formed of relatively light paper stock, a layer of material on the stock which is unaffected by the action of a liquid to be sealed therein, and a liquid material capable of forming ice permanently sealed in said bag, the bag being flexible and substantially proof against leakage and rupture as a result of repeated handling or flexing during freezing and thawing of said liquid to permit the bag 30 to flex without rupture, leakage or permanent deformation during the cycle of refrigeration of the liquid to ice and return to fluid form.

8. As a new article of manufacture employed in performing the process of forming a refrigerating unit, a bag structure of flexible paper having an inner layer of material which is unaffected by the chemical or physical action of a refrigerant when permanently sealed therein when such liquid is refrigerated to ice and then allowed to thaw, the bag structure being characterized in that it is proof against rupture as a result of repeated handling, leak-proof, strong to withstand the action of liquid therein as such liquid is refrigerated to ice, flexible to assume desired forms and to permit of change of shape as the liquid is refrigerated or the ice thaws.

CLAUDE F. BROWN.
